UNITED STATES PATENT OFFICE.

JACOB JOHNSON, OF NEWBURYPORT, MASSACHUSETTS.

RAILWAY PASSENGER-CAR.

SPECIFICATION forming part of Letters Patent No. 245,074, dated August 2, 1881.

Application filed May 7, 1881. (No model.)

To all whom it may concern:

Be it known that I, JACOB JOHNSON, of Newburyport, of the county of Essex and State of Massachusetts, have invented a new and useful Improvement in Railway Passenger Cars or Carriages; and I do hereby declare the same to be described in the following specification and represented in the accompanying drawings, of which—

Figure 1 is a top view, and Fig. 2 a sectional elevation, of part of a railway-car and two next contiguous seats thereof as provided with my invention. Fig. 3 is a horizontal section of the seat-frame, showing the auxiliary seats within the frames, and by dotted lines their positions when turned out thereof. Fig. 4 is a side view, Fig. 5 a horizontal section, and Fig. 6 a transverse section, of one of the seat-back radial arms and its connection-link, to be hereinafter explained. Fig. 7 is an elevation of the curtain-supporter and the main and auxiliary seats. Fig. 8 is a perspective view, and Fig. 9 a longitudinal section, of the said curtain-supporter.

In carrying out my invention I combine with two seats of a railway-car (preferably those next the water-closet thereof) certain appliances, as hereinafter explained, to enable me to produce a bed or lounge and an inclosure thereto, whereby an infirm person or invalid or passenger suddenly taken ill can repose or recline and be secluded from observation of other passengers. A special fixed apartment for such purpose in a railway-car being rarely used, generally cannot be otherwise utilized to advantage, and consequently it becomes very desirable to adapt in place of it some ready means by which two next adjacent seats and the contiguous space ordinarily used by four passengers may be made to assist, as occasion may require, in the formation of a structure to answer the purpose of the apartment generally termed the "saloon."

The nature of my invention is defined in the claims hereinafter made. By means of such invention the primary seats can be used in the ordinary way for sitters, or with the secondary or auxiliary seats, and other devices to be described may be utilized in producing a temporary saloon and a bed or lounge therein for an invalid or a person suddenly taken ill.

In Figs. 1, 2, and 3 of the drawings A A'

represent two next adjacent seats on one side of a railway passenger-car, part of which, in the immediate vicinity of such seats, being shown at B. In Fig. 1 a portion of a back of a third seat is shown at C, a part of the water-closet being shown at D in Figs. 1 and 2. The two main or primary seat-frames are denoted at E E', the arms of one of such frames being shown at a a in Figs. 1 and 2. Each of said seats is provided with an auxiliary seat, F, hinged or adapted to the frame of its main seat, in manner to enable it (the said auxiliary seat) to be turned or placed within the said frame into the position indicated at F' by dotted lines—that is, directly beneath the main seat—or from such position, to be turned or drawn out from beneath the main seats and arranged between the two main seats and in or about in a level with them, and against or nearly up to the side of the car, in manner as shown in Figs. 1 and 2, each auxiliary seat F having a length half or about half or less than that of its main or primary seat.

In general, I prefer to have each auxiliary seat so hinged or connected with its primary seat-frame that when turned out thereof it will be capable of being moved laterally a short distance toward the side of the car for the auxiliary seat to rest and be supported on the shelf or ledge b usually found in cars. In case, however, there is no such shelf or ledge I provide the car with one, for the support of the seats F. Besides such means of sustaining the auxiliary seats I employ a leg, c, and its carrier d. (See Fig. 3.) The carrier is a short piece of wood or metal, pivoted near one end of it to the under side of the front end of one of the auxiliary seats, and having the leg hinged to it (the said piece) at its middle, such being in order that when the auxiliary seat is out of the main seat-frames and resting upon the ledge or shelf the leg and carrier may be employed to support both auxiliary seats, they resting directly upon the carrier, and the leg being turned down and bearing at its foot on the floor of the car. The carrier, by being pivoted to the auxiliary seat, admits of the leg being turned into the oblique position shown in Fig. 3 and folded with said seat under the main seat.

In Figs. 1 and 2 the back of the longer seat

is shown at G, its two ordinary radial sustaining-arms being represented at H H. Each of the arms H I connect with the next adjacent arm a of the seat-frame E by one of two slotted or grooved links, I, pivoted to the said arm a, and connected with the radial arm by a stop washer or stud, e, which operates with shoulders f y to determine the extent of sliding movement of the arm relatively to the link. When the link is resting, as shown in Fig. 1, on the usual shoulder g of the frame the back G may be moved down from the normal position represented in dotted lines at G' into the lower and more inclined position, as indicated at G, the said back under such circumstances being usable as a head or shoulder rest or for support of a pillow for a person while reclining upon the main and auxiliary seats. On turning the back G up to the position G' each of the arms H passes into the space between two rails or flanges, h h, projecting from the link I, and by such flanges and a bolt, i, suitably applied to the link or arm, may be held from accidentally slipping backward relatively to the link.

From the above it will easily be seen how, by means of auxiliary seats adapted to operate with the main seats, substantially as described, and by the back G, combined with its seat-frame by means as explained, a lounge or bed may be easily improvised or formed of such auxiliary and main seats, or such and the back, and that when such lounge or bed may not be needed the auxiliary seat may be moved into the main-seat frames and underneath the main seats, and the back be brought up to its normal inclined position, to admit of the main seats being used in the ordinary manner—viz., by persons or passengers sitting upon them.

Above the seats I arrange a curtain-supporter consisting of two main sections, K L, and a hanger, M, they being connected together by a ring, l, going through them at one end of each. Each of the said parts K L M is hooked or bent at its outer end in manner as represented, and it may be a single rod; but I prefer to make the longer section, K, of three rods, o, connected by short links m m, and provided with a covering-sleeve, n, in manner as shown in Fig. 9.

Each sleeve is a tube to slide upon the rods, and in order to hold such sleeve in place upon the rods when it is covering the joint thereof the tube may have with one of the two rods what is termed a "bayonet-connection."

The shorter section, L, I make of two rods, o, linked together and provided with a covering-sleeve, n, to slide over and off the link. By so constructing the curtain-supporter its parts may be folded together, so as to enable it to be placed within the lower portion of the frame E, the part of such frame which is beneath the seat being made as a box or recep-

tacle to hold such supporter and the auxiliary seat F. The curtain-supporter so made is to hook upon or engage with suitable staples or devices applied to the car, the hanger M being hooked into a staple or eye projecting down from the roof of the car. The curtain-supporter thus made may be used to sustain a curtain to go around the main and auxiliary seats in order to shield from observation a person while on them.

I claim as my invention as follows, viz:

1. The combination of the main seat A and its supporting-frame E with the auxiliary seat F, adapted to the said frame, so as to be supported thereby and be capable of being turned into it beneath the main seat or out of such frame into or about into level with such main seat, substantially as set forth.

2. The combination of the two next contiguous main seats A A' and their supporting-frames E E' with the two auxiliary seats F F, connected with and adapted to the said frame, so as to be capable of being moved into such and underneath their seats or out of such frames and into or about into level with and between the said seats and close together, all substantially as and for the purpose set forth.

3. In combination with the main seat A and its supporting-frame E, and the ledge or shelf b or bearing at the side of the car, the auxiliary seat F, adapted to the frame, so as to be capable of being turned into and out of such frame, and moved laterally on and off the ledge or bearing, all substantially as set forth.

4. The combination of the connection-links I, substantially as described, with the seat-supporting frame E, and the back G, and its radial arms H, such arms being adapted to the links and the latter to the frame, essentially in manner as explained.

5. The combination of the leg c and its carrier d, connected with each other and one of the auxiliary seats, in manner described, with the main and auxiliary seats A A' F F, combined and to operate with the seat-frames E E', essentially as set forth.

6. The curtain-supporter consisting of the two main sections K L and the hanger M, provided with hooks, and connected substantially as set forth.

7. In the curtain-supporter, the hooked hanger M, in combination with the two sections K L, as composed, not only of two or more rods linked together, but of a covering-sleeve to each connection or joint, as described, such sleeve being to slide on the rods and on and off their connection or joint link, as set forth.

JACOB JOHNSON.
